United States Patent Office.

GEORGE BRILL, OF PHILADELPHIA, PENNSYLVANIA.

Letters Patent No. 62,931, dated March 19, 1867.

IMPROVED AXLE-BOX.

The Schedule referred to in these Letters Patent and making part of the same.

TO ALL WHOM IT MAY CONCERN:

Be it known that I, GEORGE BRILL, of Philadelphia, Pennsylvania, have invented an improvement in Axle-Boxes; and I do hereby declare the following to be a full, clear, and exact description of the same, reference being had to the accompanying drawing, and to the letters of reference marked thereon.

My invention consists of a sliding door having a pin with a collar, the whole being constructed and adapted to an axle-box substantially as described hereafter, so that the door may be securely packed and firmly held in its place by the said pin and collar, and easily withdrawn after simply turning the pin to a limited extent.

In order to enable others skilled in the art to make and use my invention, I will now proceed to describe its construction and operation. On reference to the accompanying drawing, which forms a part of this specification—

Figure 1 is a longitudinal section of my improved axle-box.

Figure 2, a transverse vertical section on the line 1 2, fig. 1.

Figure 3, a plan view; and

Figure 4, a plan view of part of the box as it appears when the sliding door has been removed.

Similar letters refer to similar parts throughout the several views.

A is the top, A' the bottom, B the rear, and B' the front of the permanent portion of the box, D being the usual step, bearing against the under side of the top A, and being adapted to the journal E of the axle. F is the detachable front or door, the lower end of which bears upon the upper edge of the permanent front B' of the box, where a lip, x, fitting in a recess in the door prevents the latter from being moved outwards, the upper horizontal portion of the door fitting against the front end b of the top A of the box. The door is adjusted to its place in front of the box by sliding the former downwards from above, there being on the inside of the box, and at each side of the same, a rib, y, against which bears the door, so that the latter cannot be moved inwards. A flat edge, w, is thus presented on three sides of the door, and this edge is grooved for the reception of a packing strip, G, which, bearing against the box, prevents the escape of lubricating material from the latter. In the upper portion of the door turns a pin, H, having at its upper end a collar, h, and a square or other suitably-formed head, i, there being at the lower end of the pin a collar, m, against which bears a spiral spring, n, contained in a recess in the door, this spring having a tendency to depress the pin H, and to cause the collar h to bear with such force on the top of the door that the pin cannot be turned without considerable effort. In place of this spring and the collar m, the pin may be so tightly riveted to the door that it cannot be turned without an effort. As seen in figs. 1 and 3, a portion of the collar h projects into and fits snugly in a recess formed in the end b of the top A of the box, thereby locking the door to the latter so securely that it cannot possibly be shaken loose by the jarring of the box. It will be seen on reference to fig. 3 that a portion of the collar h is cut away at y, so that when the pin H has been so far turned that this cut-away portion coincides with the front b of the top A of the box the door is at liberty to be elevated from its place. A small pin, q, projects from the collar h into a segmental recess (shown in dotted lines, fig. 3) in the door. When the pin is at one end of this recess the pin H has been turned to an extent sufficient to lock the door to the box, and when the pin q is at the opposite end of the recess, the collar h is in such a position as to permit the removal of the door.

I claim as my invention, and desire to secure by Letters Patent—

1. The sliding door F, and pin H, with its collar h, the whole being constructed and adapted to an axle-box substantially as and for the purpose herein set forth.

2. The ribs y y and lip x, arranged on the box for the retention of the door, as set forth.

3. The packing strip G, adapted to the door and box, as described for the purpose specified.

In testimony whereof I have signed my name to this specification in the presence of two subscribing witnesses.

G. BRILL.
